CLAIM

The ornamental design for a solar powered toy powered helicopter, as shown and described.

DESCRIPTION

FIG. 1 is a top plan view of a solar powered toy helicopter showing my new design;
FIG. 2 is a side elevational view thereof, the side opposite being substantially a mirror image;
FIG. 3 is a bottom plan view thereof;
FIG. 4 is a front elevational view thereof; and
FIG. 5 is a rear elevational view thereof.

FIG. 4

FIG. 5
